(57) **CLAIM**

The ornamental design for a body cleansing sponge, as shown and described.

DESCRIPTION

FIG. 1 shows a perspective view of a body cleansing sponge; FIG. 2 shows a top plan view of the body cleansing sponge; FIG. 3 shows a bottom plan view of the body cleansing sponge;

FIG. 4 shows a right-side elevation view of the body cleansing sponge;

FIG. 5 shows a left-side elevation view of the body cleansing sponge;

FIG. 6 shows a front elevation view of the body cleansing sponge; and,

FIG. 7 shows a rear elevation view of the body cleansing sponge.

The broken lines shown in the Figures show portions of the shower accessory which form no part of the claimed design.

1 Claim, 5 Drawing Sheets
